US00D918400S

(12) **United States Design Patent** (10) Patent No.: **US D918,400 S**
(45) Date of Patent: **** May 4, 2021**

(54) **HALLUX VALGUS CORRECTOR**

(71) Applicant: **Qingli Ma**, Shandong (CN)

(72) Inventor: **Qingli Ma**, Shandong (CN)

(**) Term: **15 Years**

(21) Appl. No.: **29/693,910**

(22) Filed: **Jun. 6, 2019**

(51) LOC (13) Cl. **24-04**

(52) U.S. Cl.

USPC **D24/192**

(58) **Field of Classification Search**

USPC D24/155, 192, 187-190, 200, 206, 215

CPC A61F 5/14

See application file for complete search history.

(57) **CLAIM**

The ornamental design for a hallux valgus corrector, as shown and described.

DESCRIPTION

FIG. 1 is a perspective view of a hallux valgus corrector showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a usage state diagram thereof.

The broken lines in the FIG. 8 depict environment only and form no part of the claimed design.
